UNITED STATES PATENT OFFICE

WILLIAM DANA SEIBERT, OF BROOKLYN, NEW YORK

BUCKLE

Application filed January 5, 1932. Serial No. 584,833.

The object of my invention is to provide a novel and useful buckle of simple and efficient construction intended primarily for use for fastening the straps on binders, but adapted for other uses to which a buckle may be put. I attain these and other objects of my invention by the device illustrated in the accompanying drawing, in which—

Figure 1 is a perspective view of the buckle 10 in position to fasten a strap around a package;

Fig. 2 is a section on line 2—2 of Fig. 1 of the drawing showing the buckle in unlocked position;

Fig. 3 is a similar section showing the buckle as it is being moved toward the locked position shown in Fig. 1;

Fig. 4 is a perspective view of the buckle detached from the strap which it fastens;

Fig. 5 is a similar view showing a modification having the arched link 7'; and

Fig. 6 is a perspective view of a modified form of the buckle having the link 7' toothed.

Like characters of reference designate like parts in each of the views.

Referring to the accompanying drawing, there is illustrated a packaged article A encircled by a strap S, one end of which strap is provided with a stitched or other suitable loop S1, the free end of the strap being designated as S2.

The buckle consists of a cross bar 1 having side bar members formed at right angles to the cross bar and diagonally (or inwardly) bent portions 3 which meet at 6 and are suitably bent to form the loop 4 which functions as a finger hold, the ends of the loop being preferably joined at 5.

I provide a link 7 having eyes 8 loosely and slidably mounted on the end portions 2 to permit a limited movement of the link 7. In use the looped end of the strap S1 is stitched around the cross bar 1, the strap is extended around the article to be fastened and the free end S2 is inserted between the cross bar 1 and link 7 as shown in Fig. 2 and the buckle is then swung by means of loop or finger hold 4 in the direction indicated in Fig. 3 to a position substantially like that shown in Fig. 1. The link 7 serves to fric-

tionally engage and thus lock the strap in the buckle.

In the modified forms of the buckle shown in Fig. 5, the link 7' is arched or curved so that its ends will more snugly engage the strap while the central portion is substantially free from the strap.

In Fig. 6 there is illustrated a further modified form of the invention in which there is provided a cross link 7" which is toothed or roughened to more effectively engage the strap, this form of the invention being necessary only where a very considerable tension is applied to the strap.

The operation of the device has been described in Figs. 2 and 3 of the drawing.

It is within the contemplation of my invention to make the buckle either of round wire or of flat strips of metal; and to modify the shape of the loop member as desired.

What I claim is:—

1. In a buckle, the combination of a cross bar, having sides bent at right angles thereto, diagonally bent portions terminating in a looped element so formed and positioned as to be used for operating the buckle, and a link having its ends formed into eyes loosely engaging the aforesaid sides of the buckle to permit of insertion of a belt or strap between the link and the cross bar and adapted to frictionally but releasably engage the belt or strap to fasten same in an engaged position or to release same by a swinging movement of the buckle.

2. In a buckle, the combination of a wire cross bar, having sides bent at right angles thereto, diagonally bent portions terminating in a looped element so formed and positioned as to be used for operating the buckle, and a wire link having its ends formed into eyes loosely engaging the aforesaid sides of the buckle to permit of insertion of a belt or strap between the link and the cross bar, said link being arched to cause its ends to tightly engage the belt or strap.

3. In a buckle, the combination of a wire cross bar, having sides bent at right angles thereto, diagonally bent portions terminating in a looped element so formed and positioned as to be used for operating the buckle,

and a link having its ends formed into eyes loosely engaging the aforesaid sides of the buckle to permit of insertion of a belt or strap between the link and the cross bar, said link being roughened to frictionally engage the strap or belt to hold same against a considerable tension.

4. In a buckle, the combination of a cross bar, having sides bent at right angles thereto, said sides then being inwardly bent, said 10 inwardly bent portions being formed into a finger hold element, and a single link having eyes at its ends loosely mounted on the sides, said link being slightly offset from the plane of the buckle frame, whereby a strap or belt 15 may be frictionally engaged by the said link and the aforesaid cross bar by manually operating the main portion of the buckle with a swinging movement.

WILLIAM DANA SEIBERT.
